BATTERY-OPERATED CHART DRIVE

Robert B. Stiens, Silverton, Ohio, assignor to Palmer Instruments, Inc., Norwood, Ohio, a corporation of Ohio

Filed Dec. 5, 1962, Ser. No. 72,732

Term of patent 14 years

(Cl. D52—6)

Des. 200,797

PAGE 2

FIG. 3

FIG. 4

FIG. 5

FIG. 6

FIG. 1 is a front view of a battery-operated chart drive, showing my new design.

FIG. 2 is a side elevation thereof.

FIG. 3 is a top plan view thereof.

FIG. 4 is a view taken on line 4—4 of FIG. 1.

FIG. 5 is an end elevation of the battery container of FIG. 1.

FIG. 6 is a view taken on line 6—6 of FIG. 1.

FIG. 7 is a rear view of FIG. 1.

FIG. 8 is an elevation of the opposite side of FIG. 2.

In FIGS. 1, 2, 7, and 8 the cable is shown broken away to indicate indeterminate length.

I claim:

The ornamental design for a battery-operated chart drive, as shown and described.
